Original application February 23, 1935, Serial No.
7,742. Divided and this application January 3,
1938, Serial No. 182,992

2 Claims. (Cl. 226—75)

This invention relates to improvements in article transferring mechanism. More particularly this invention relates to rotary type bottle filling and capping machines in which the filling, capping and transferring mechanisms are symmetrically arranged to facilitate changing of the machine from a righthand to a lefthand type machine and in which the filling, capping and transferring mechanisms are accurately synchronized in their relative motions. In the rotary type of bottle fillers and cappers now available, substantial alterations of the machine are required to change the same from a righthand to a lefthand machine and the presently available machines, in which the synchronization of the filling, capping and transferring mechanisms is necessary, often become unsynchronized as the various driving elements of the individual devices forming a part of the machine become worn through normal usage of the mechanism.

This application is a division of application Serial No. 7,742, filed February 23, 1935, entitled "Bottle filling mechanism," on which United States Patent No. 2,122,149 has been granted.

The presently described and claimed aspect of the invention relates to a transferring mechanism of general application exemplified in the bottle handling parts of a bottle filler and capper. The aspect of the invention relating to the infeed gate or throat, particularly disclosed in Figure 2, is described and claimed in a co-pending application which is a division of this application, filed November 4, 1940, bearing Serial No. 364,145, now Patent Number 2,300,298, dated October 27, 1942.

It is the primary object of the invention to provide a novel, simple, and reversible arrangement for the use of a single conveyor in feeding articles, such as empty bottles, to and receiving articles, such as full bottles, from stations, such as a bottle filling and capping machine.

More specifically stated, it is an object of the invention to provide an improved organization of several tables and star wheels with reference to the infeeding and outfeeding conveyor and the work guides so that the movement of the work is facilitated, stoppage and breakage are avoided, and so that certain parts are preferably interchangeable to adapt the machine for righthand or lefthand operation.

A further object of the present invention is to provide a driving mechanism in a rotary type bottle filling and capping machine in which the perfect timing of the rotary filling table, the rotary capping table and the intermediate rotary transferring mechanism is secured and main-

tained by the employment of common means, such as a chain, for the driving of all of the individual mechanisms from a single source of power whereby, upon the normal wearing of the driving elements for the individual devices, the slack or excessive looseness will be automatically absorbed by the automatic tightening of the single driving chain thereby maintaining perfect synchronization of the inter-coating elements.

10 A still further object of the present invention is to provide a bottle filling and capping machine in which a portion of a single flight of a continuous conveyor may be used as the supply conveyor while the remaining portion of the single flight 15 of the conveyor may be used as the discharge conveyor; in which the bottle receiving, transferring and discharge mechanisms of the bottle filler and capper are arranged symmetrically with the bottle filling and capping devices; in which 20 the single conveyor is arranged tangentially to the receiving and discharge transfer mechanisms; and in which the capping mechanism, which also comprises one of the transferring mechanisms, may be interchangeably positioned upon the base of 25 the bottle filler and capper without altering the symmetrical arrangement of the bottle filling mechanism, the capping mechanism and the various transfer mechanisms so as to permit the ready interchange of the combined mechanisms 30 from a righthand to a lefthand type machine.

Other important objects and features of this invention will become more apparent upon examination of the details of construction, as disclosed in the accompanying drawings, all of which 35 will be first fully described and then specifically pointed out in the appended claims, reference being made from time to time to the drawings in which:

Figure 1 is a view of the improved machine as 40 it appears partially in side elevation and partially broken away to a longitudinal vertical section.

Figure 2 is a plan view of the device shown in 45 Figure 1 with the capping head removed and the milk admission pipe cut away.

Figure 3 is a schematic plan view of the driving connections.

Figure 4 is an enlarged detail view in perspective, showing one of the star wheels as used for 50 transferring bottles from the conveyor turntable to the capper.

Figure 5 is an enlarged detail view in axial section showing the mounting for the unloading star wheel.

55 Figure 6 is an enlarged detail view in axial sec-

tion showing the mounting for the capping device and its turntable.

The general organization of the machine is the same whether the filling operation is conducted by gravity or by vacuum. This general organization most clearly appears in Figures 1 and 2. In the drawings, in which like numerals are used to identify like elements, 15 represents a base housing the driving connections and preferably supported by suitable legs. At one end of that base is the bearing 16 for the turntable 17 which carries the individual work supports and the table of the filling mechanism hereinafter to be described by way of illustration.

At one corner of the other end of the base 15 is a bearing 18 for the capper turntable 19, which is also provided with bottle supports and is assembled on a shaft 20 which carries a conventional capper head 21 vertically adjustable upon the shaft by means of a screw 22 journaled in an arm at the top of the shaft and the nut 23 carried by the capper head.

Spaced above the hollow base 15, at the level of the lower bottle supports, is a table 25 across which the bottles are loaded, unloaded, and transferred between the filling and capping mechanisms. A single conveyor 26 is flush with the edge of the table and serves to supply empty bottles and remove filled bottles from the machine. It operates tangentially with reference to the loading star wheel 27 and the unloading star wheel 28. The transfer star wheel is shown at 29. A suitable bottle guide member 30 of the form clearly indicated in Figure 2 has surfaces concentric with the axes of each of the three star wheels to co-operate therewith in guiding the movement of bottles.

It is to be noted that the machine is assembled symmetrically with reference to a longitudinal center line through the turntable of the filler. This makes it possible readily to convert the machine for either right or lefthand operation. The capper may be interchanged with the idler pulley shown at 72 (Figures 2 and 3); the conveyor 26 may be moved to cut across the lower corner rather than the upper corner as viewed in Figure 2; and the star wheels may simply be inverted upon their respective shafts to adapt them for operation in the other direction, the motor and its bracket being transferred to the other side of the base for such operation.

Throat mechanism is preferably provided to guide the bottles from the conveyor onto the table, 25 and within the interdental pockets of the star wheel 27. In the absence of an appropriate throat mechanism the tip of a star wheel tooth will occasionally engage the side of a bottle under substantially balanced conditions of pressure so that the bottle will be held to the guide rail or fence without tending to move either forwardly or rearwardly thereon. Ultimately it may either be crushed or may cause breakage of the machine or may snap from its position with such force as to break itself or other bottles. In order to guard against these contingencies and at the same time to provide a throat which is adjustable for handling bottles of differing sizes, the mechanism shown in Figure 2 is employed, which is particularly described and claimed in the co-pending application which is a division of this application as previously identified.

Fixed vertical pins are provided at 260, 261 and 262. The arm 263, which has spaced bottle engaging portions at 264 and 265 and an intervening depression, is fulcrumed upon pin 261. The

bottle engaging head 264 of this arm stands out above a portion of the conveyor in a position such as to force toward the star wheel bottles which are approaching on the conveyor. In the event that there is a gap between the end of the arm 263 and the side wall 26' which parallels the path of conveyor 26, a slide bar extension wall element 279 is provided. The slide bar extension wall element 279 is pivoted to the head portion 264 of arm 263 and in sliding connection with the fitting 281 which is located at the end of wall 26'.

As the bottle passes around the head 264 of the pivoted arm 263 the lateral motion given to it will be in a direction opposite to that of the adjacent portions of the star wheel. The bottle will be thrust toward one of the star wheel pockets on a path such that it will be difficult, if not impossible, for the bottle to be caught by the end of the star wheel tooth. The arm 263 is yieldable under the thrust of the compression spring 266 about its pivot 261 and this yielding movement is such that it will not only relieve a bottle of pressure but will tend to assure its firm engagement in the pocket. As the star wheel rotates, any bottle which might be caught on the head portion 264 of the arm 263 will be pushed from said head portion into the adjacent recess in the arm and its slight advance will relieve the pressure momentarily and seat the bottle in the star wheel pocket in its proper position. It is the function of the second projection 265 on arm 263 to make sure that the bottle remains in the pocket when it is delivered by the star wheel against the guide arm 267 which terminates flush with the guide member 30 referred to above.

Guide arm 267 is likewise pivotally mounted, being carried on fulcrum pin 260 and provided with a projecting finger at 268 engaged by compression spring 269 which, like compression spring 266, is on rod 270.

Carried by the fixed pin 261 is a boss 271 in which is threaded a screw 272 turned by crank 273. This crank is fixed in an adjusting lever 274 so that the rotation of the crank will oscillate the adjusting lever about the fixed pin 260. This adjusting lever has an arm 275 carrying the spring guide rod 270 and another arm 276 which is mounted on rod 277 in engagement with the compression spring 278 by means of which its motion is yieldably transmitted to the throat member 280 mounted on fulcrum pin 262.

It will be apparent that when it is desired to adjust the machine to handle small bottles and to constrict the feeding throat accordingly, the crank 273 may be turned in a direction to move lever 274 counter-clockwise about fulcrum pin 260, thereby swinging arm 275 in a direction to push the spring guide rod 270 downwardly to the left as viewed in Figure 2. By increasing the compression on spring 266 and correspondingly increasing the compression on spring 269, this movement of the spring guide rod will result in shifting inwardly the free ends of lever arm 263 and guide arm 267 while at the same time shifting inwardly the free end of the throat member 280 on the opposite side of the conveyor. A reverse movement of the screw will adjust the parts in an opposite direction.

When the machine is changed over to a left-hand machine the infeed gate mechanism or throat mechanism, as above described, must be reconstituted to function in its new position. As to a few of the parts new castings are substituted, but the majority of the parts may be used by simply inverting them upon their respective pivot

posts, whereupon they will function in their new position in a manner corresponding to that above described.

The general organization above described may be used without change, both for gravity fillers and for vacuum fillers. The driving connections, which are likewise common to both types of machines, will now be described.

The driving motor 40 is mounted on a slide 41 on bracket 42 on the outside of the base. The 10 driving pulley 43 is preferably divided into two parts subject to the compression of a spring 44, whereby the speed ratio may be varied somewhat by adjusting the motor slide 41 to force the belt 45 to a greater depth between the component parts of the pulley.

The power received by the main drive shaft 47 from pulley 46 is delivered through a worm 60 of worm gear 61 to a vertical shaft 62 upon which the star wheel 28 is mounted. Angular adjustment of the star wheel on the shaft may be made by loosening the nut 63 which clamps the tapered star wheel hub 64 between the cones 65 on the shaft. Star wheels 27 and 29 are detachably engaged on pins 65' carried by rotors 66 and 67 respectively, (rotor 66 not shown) which are similarly angularly adjustable on shafts 78 and 74. The freedom with which the star wheels 27 and 29 are detachable from pins 65' enables the operator readily to replace these star wheels when the machine is to handle a different size of bottle. Each of the star wheels 27 and 29 performs a positioning function in properly registering the bottle on one of the supports by which it is to be lifted. It is not necessary to replace star wheel 28, since this star wheel merely discharges the bottles onto a conveyor on which no particular registration is important.

A single chain 70 (Figure 3) passes about a driving sprocket 71 on the vertical shaft 62 and thence passes over an adjustable idler sprocket 72 and a sprocket 73 on star wheel shaft 74, and a sprocket 75 on main turntable shaft 76, and a sprocket 77 on star wheel shaft 78, and finally over a sprocket 79 on the shaft 20 of the capping turntable. Thus 45 all the vertical shafts are driven by a single chain from the worm gear 61 and shaft 62.

In the above identified parent application minute descriptions of various elements appear and, accordingly, further detailed explanations in this case will not be made of the turntable 17, bottle supports 92 in annular series thereabout, the cam rollers 99, the cams 106 and 108 which act thereon in the lowering of the bottles, and the vacuum filling mechanism including the reservoir 135, the vacuum chamber 144, the filler heads 160, the control valves 162, the vacuum pump 149, and the milk separating and return connections 147, 150, 151 and 152.

The operation of the apparatus may be summarized as follows.

Empty bottles arrive on conveyor 26 and, according to their size, are fed by interchangeable star wheels 27 onto the filler turntable which includes vertically adjustable bottle supports.

After the bottle has been filled the roller 99 of the individual bottle support rides between a pair of lowering cams, and the push rod 96 which controls the supporting clutch is concurrently released to allow the support to move downwardly. When the support is moved to the level of the table surface 25 star wheel 29 transfers the bottle from the filler turntable to the capper turntable which has similar supports whereon the individual bottles are successively raised to the cappers.

In the capper turntable, however, there is no means for locking the supports in an elevated position, and upon the completion of the capping operation the bottles are lowered once more to table 25 and discharged by star wheel 28 onto the outgoing end of conveyor 26.

In the operation of the mechanism as above identified it is obvious that any wear of the single driving chain 70 or the various sprockets which are driven by this chain will all automatically be taken up by the adjustable idler sprocket, as previously described, thereby preventing the development of any slack motion in the synchronized action of the filling turntable, the bottle capper and the receiving, transferring and discharge star wheels.

In the present invention a bottle filler and capper has been provided in which the bottle filling turntable or sprockets, and the receiving, transferring and discharge star wheels or transfer mechanism are all synchronized in their relative motions and are all symmetrically arranged on the base for the machine so as to be adaptable for use with a single flight of conveyor which comprises both the infeed and the discharge conveying mechanisms.

Due to the symmetrical arrangement of the various elements of the machine as above described, a bottle filler and capper has been provided which may be readily transformed from a lefthand machine to a righthand machine by the mere interchange of the chain idling mechanism and the capping mechanism which are symmetrically positioned in the base and which, when interchanged, permit the re-arrangement of the supply and discharge conveyor so as to feed bottles to and discharge bottles from the other side of the bottle filling and capping mechanism. All of the bottle filling, capping and transferring 40 mechanisms are individually powered for synchronous operation from a single drive chain whereby, even though the individual elements may wear and the driving chain may also wear, the synchronized operation and timing of the elements is maintained.

In the accompanying drawings the preferred embodiment of the invention has been illustrated. Obviously various modifications of the invention may become apparent to those skilled in the art upon reviewing the invention herein disclosed. The invention, however, is not to be restricted except in so far as it is necessary in view of the prior art and the spirit of the appended claims.

I claim:

1. A receptacle handling apparatus comprising the combination with a suitable support and a turntable rotatable thereon, of a pair of star wheels located symmetrically with reference to a radius of said turntable for the loading and unloading of receptacles, driving shafts for said star wheels upon which said star wheels are invertibly mounted to be operative for loading or unloading according to the direction of rotation of the shafts, means in said base for driving said star wheel shafts and turntable, an operating sprocket and an idler sprocket also driven by said means and symmetrically located at opposite sides of said radius and interchangeable with each other, and work-operating mechanism removably mounted on said base and operatively connected with said operating sprocket to be actuated thereby in either position of the sprocket.

2. A receptacle handling apparatus comprising the combination with a suitable support and a receptacle turntable rotatable thereon, of a pair

of star wheels located symmetrically with reference to a radius of said turntable for the loading and unloading of receptacles, driving shafts for said star wheels upon which said star wheels are invertibly mounted to be operative for loading or unloading according to the direction of rotation of the shafts, means in said base for driving said star wheel shafts and turntable, an operating sprocket and an idler sprocket also driven by said means and symmetrically located at opposite

5

10

sides of said radius and interchangeable with each other, work operating mechanism removably mounted on said base and operatively connected with said operating sprocket to be actuated thereby in either position of the sprocket, and an unloading star wheel positioned substantially on said radius and arranged to be operated for the unloading of the said mechanism in either of the aforesaid positions of the mechanism.

ADOLPH J. LIPPOLD.
